UNITED STATES PATENT OFFICE.

CHARLES E. YOUNT, SR., OF HARRISBURG, PENNSYLVANIA.

SUNBONNET.

No. 833,950.

Specification of Letters Patent.

Patented Oct. 23, 1906.

Application filed April 16, 1906. Serial No. 311,900.

To all whom it may concern:

Be it known that I, CHARLES E. YOUNT, Sr., a citizen of the United States of America, and a resident of Harrisburg, in the State of Pennsylvania, have invented a new and useful Improvement in Sunbonnets, of which the following is a specification.

This invention relates to those articles of headwear for women and children known as "sun-hats" or "sunbonnets;" and it consists in certain novel features of construction hereinafter described and claimed.

The objects of the invention are to adapt the article to be readily and effectively laundered before and after use; to adapt the same to be packed perfectly flat for storage and shipment, whereby great saving in paper boxes, wooden packing-cases, and freight and cartage expenses is effected; to adapt the sunbonnet to be held in the shape in which it is worn by a single draw-string occupying a straight pocket in a combined puff and cape portion of the article, and to render the article of neat and attractive appearance in the shape in which it is worn, with a flaring crescent-shaped crown that almost entirely encircles the head, and may be and preferably is tastefully trimmed by a ruffle attached to its convexly-curved front edge from one extremity thereof to the other without demanding a box of materially greater size than is necessary to accommodate the flattened crown portion itself.

Other objects of the invention are to wholly dispense with detachable parts and open seams, with their fastenings, and especially hooks and eyes and the like, so as to avoid the production of rust-spots, and to obviate the employment of elastics, which are liable to become prematurely inoperative and are objectionable because of their pressure upon the head.

A sheet of drawings accompanies this specification as part thereof.

Figure 1 is a top or back view of the sunbonnet as flattened and folded in packing the same for shipment or for storage. Fig. 2 is a face view of the same in its flattened condition, but unfolded; and Figs. 3, 4, and 5 are respectively a front view, a side view, and a back view of the sunbonnet in the shape in which it is worn.

Like reference characters refer to like parts in all the figures.

The improved sunbonnet includes a relatively stiff or stiffenable crown portion *a*,

that in its flattened condition is crescent-shaped, as best shown in Fig. 2. To the concavely-curved rear edge of said crown portion *a* one edge of a combined puff and cape portion *b c* is permanently or inseparably attached at all points with such fullness in the puff portion *b* as may be desired, such fullness being provided for in customary manner by gathering the front edge of the puff portion. The puff portion *b* terminates in a straight draw-string pocket 1, extending in a straight line from one extremity of said crown portion *a* to the other, within which a draw-string 2 is fastened at one of said extremities, protruding from the pocket at its other end. A cape *c* of suitable proportions, adapted to be folded back upon the puff portion *b* when the sunbonnet is flattened, is preferably and conveniently made in one piece with said puff portion *b* and connected therewith by said pocket 1. (Compare Figs. 1 and 2.) A pair of strings 1' and 2', adapted to be tied beneath the chin, are attached to the front edge of the crown portion *a* near its respective extremities. A second pair of strings 3 and 4, adapted to be tied together or fastened in any approved way, are attached at the back of the sunbonnet to the respective extremities of the crown portion *a* and serve to mask the draw-string pocket 1 and to render more sightly the back of the sunbonnet as worn. (See Fig. 5.) The convexly-curved front edge of the crown portion *a* is preferably provided by way of trimming with a fluted ruffle *d*, with or without an edging *e* of lace or the like, said ruffle *d* tapering in width toward both extremities of the crown portion *a*, so as to occupy little, if any, additional room in the packing-box and to present a pleasing appearance on the article as worn. (See Fig. 4.)

In converting the sunbonnet from its flattened and folded condition represented by Fig. 1 to the shape in which it is worn, as represented by Figs. 3, 4, and 5, it is only necessary to pull together the extremities of the crown portion *a* and to gather the lower edge of the puff *b* as tightly as possible by means of the draw-string 2, which is then fastened, and to tie together or otherwise to fasten the supplemental strings 3 and 4 in the crease between the puff *b* and the cape *c* at the back of the sunbonnet.

The edging *e* or the ruffle *d* as a whole may obviously be omitted without materially changing the sunbonnet, as may also the

supplemental strings 3 and 4, and other like modifications will suggest themselves to those skilled in the art.

Having thus described said improvement, 5 I claim as my invention and desire to patent under this specification—

A launderable sunbonnet including a stiff crescent-shaped crown portion having a concavely-curved rear edge and a convexly- 10 curved front edge extending from one lateral extremity thereof to its other lateral extremity, a relatively soft puff portion inseparably attached at all points to said rear edge and provided with a straight draw-string pocket 15 and a draw-string within said pocket extending from one of said extremities of the crown

portion to its other extremity, and a cape inseparably united with said puff portion along said draw-string pocket and adapted to be folded upon said puff portion when the article is flattened, the whole being adapted to be flattened and folded within a small compass to economize space in boxing the article and to facilitate laundering the same, and adapted to be adjusted and held in shape by 20 said draw-string without additional fastenings, substantially as hereinbefore specified. 25
